UNITED STATES PATENT OFFICE.

TURNER WILLIAMS, OF PROVIDENCE, RHODE ISLAND.

IMPROVEMENT IN SELF-ADJUSTING PIPE-WRENCHES.

Specification forming part of Letters Patent No. **136,351**, dated February 25, 1873.

To all whom it may concern:

Be it known that I, TURNER WILLIAMS, of Providence, in the county of Providence and State of Rhode Island, have invented a certain new and useful Improved Self-Adjusting Wrench, of which the following is a specification:

The Nature of the Invention.

The nature of my invention consists in combining in a wrench a fixed jaw having a convex toothed bearing-surface with a corresponding eccentrically-moving concaved jaw; the moving jaw being so pivoted to the fixed jaw that, when the wrench is applied, the tendency is for the movable jaw to swing toward the fixed one, and thus grasp the intervening object. The moving jaw is also combined with a spring so as to be impelled toward the fixed jaw.

By this arrangement of a swing scroll-jaw no adjustment is required, as the wrench may be applied to any pipe or bolt within its range, and will grasp the same automatically.

Description of the Drawing.

Figure 1 is an elevation of my invention. Fig. 2 is a section of the same.

General Description.

Let A represent the handle, to which the fixed jaw B is attached or forms a part of. This jaw B is curved and notched, as shown, the cam being eccentric to the pivot C, upon which the movable jaw D swings. The movable jaw D is concave, and so formed and connected to the fixed jaw B that, as it swings over in the direction indicated by the arrow in Fig. 2, it approaches the fixed jaw, in fact may close onto it, as shown in Fig. 1. F is a spring, which acts through the block E upon the back of the movable jaw, and serves to close it upon the fixed jaw.

If desirable, the spring F may be dispensed with, and a lever to be moved by hand substituted for it.

I claim as my invention—

The combination of the jaw D, the block or tumbler E, and spring F with the fixed jaw B, operating substantially as described, and for the purpose set forth.

TURNER WILLIAMS.
